UNITED STATES PATENT OFFICE.

FELIX BAENTSCH, OF BERLIN-CHARLOTTENBURG, AND ALFRED STOBER, OF BERLIN, GERMANY.

SMOKE DAMPER.

Application filed April 13, 1926, Serial No. 101,760, and in Germany April 23, 1925.

It is a well known fact, that after each run of periodically operated boilers, furnaces, ovens and the like a substantial portion of the heat stored up therein escapes during the stand-still periods to the stack on account of the unavoidable leakages of the smoke dampers and must be reproduced by means of a considerable excess consumption of fuel at the next boiler heating period. It has therefore already been proposed to arrange an air inlet passage between the boiler and the usual smoke damper in order that the stack draft may be able to suck in atmospheric air directly instead of from the heated flues of the boiler. Since however with the known construction this air inlet passage has an immediate communication with the boiler and its flues it was unavoidable that on account of the buoyancy of the hot air within the boiler atmospheric cold air was also sucked through the air inlet passage into the hot boiler, whereby the purpose of the arrangement was practically rendered illusory.

In order to do away with this draw-back we provide according to this present invention within the flue leading from the boiler to the stack and by means of a second additional damper a special separate space or compartment between the boiler and the stack, which space or compartment has a leakage connection with the stack and is adapted to communicate with the outer atmosphere, care being taken, that no bypass communication, such as for example a direct leakage connection past the dampers and at the exclusion of a said space or compartment, may exist between the stack and the boiler sides of the smoke flue. As a result of such arrangement a pressure equal or substantially equal to atmospheric pressure is produced between the smoke dampers constituting the said space or compartment, whereby an escape of heat from the boiler furnace or the like is successfully prevented, as will be described more in detail hereinafter.

In the drawings illustrating some embodiments of our invention—

Fig. 1 illustrates the general arrangement according to our invention in connection with the boiler,

Fig. 2 is a sectional view of the air inlet valve or mechanism,

Fig. 3 is a sectional view of a modification

of the compound damper taken along line C—D Fig. 5,

Fig. 4 is a vertical cross section along line E—F Fig. 3,

Fig. 5 is a plan view of the modification 60 Fig. 3, partly in section along line A—B Fig. 3.

According to Fig. 1 of the drawing the combustion gases of boiler 1 pass as usual through a flue 2 to the stack 3, a shutting-off member, in this particular instance, an ordinary smoke damper 4, being arranged within flue 2 between the boiler and the stack. Between the damper 4 and the stack 3 we arrange according to our present invention a second slide or damper 5 thus permitting to shut-off or separate from flue 2 a closed separate space or compartment 6, when both slides or dampers 4, 5 are in their lowered or operative position as shown in 70 Fig. 1. The space or compartment 6 is adapted to communicate with the outer atmosphere by means of an orifice or passage 19 being controlled by an air inlet or valve mechanism 7. This mechanism comprises a 80 seating member 8 having a peripheral groove or channel 9 adapted to receive a dip-bell or valve member 10. The channel 9 is filled with loose dry sand or fine-grained lead-shot, the inner edge 11 of member 10 being so bevelled as to urge the sand or the like towards the inner face of channel 9. The bell 10 is guided by a bracket 12 (Fig. 2) and attached to a cable 14 passing over sheaves 13 and having at its end a counter-weight 15 with which a tappet 16 is adapted to engage. This tappet 16 is attached to the rope or cable 17 carrying the slide or damper 5 and having at its outer end a counter-weight 18, as shown. The tappet 95 16 is so attached to cable 17 that it engages weight 15 only and thereby lifts the valve member 10 from its seat, when the damper 5 is nearly closed. Air is thus automatically admitted to the space or compartment 6 whenever the two dampers are moved into their lowered or operative position.

In order that the operation of our improved damper arrangement so far described may be readily understood it should be borne in mind that the two slides or dampers 4 and 5 are moving in their guides with a certain amount of unavoidable leakage. If both dampers 4 and 5 are in their operative position as shown in Fig. 1 the stack 3 has 110

communication with the space 6 through the leakage of damper 5 so that it can suck off cold atmospheric air entering through passage 19. The stack 3 has however no direct leakage or by-pass connection at the exclusion of or around the space 6 with that part of flue 2 which is located between the slide or damper 4 and the boiler 1 so that no heat can be carried off past such by-pass around space 6 into and through the stack 3. Since the dynamic pressure difference between the stack 3 and space 6 is far greater than that between the boiler 1 and space 6 practically no atmospheric air will be sucked from space 6 and through the leakage between damper 4 and its guide into the boiler 1, so that the same will retain substantially all of the heat stored up in it, with the only exception of the slight heat losses by radiation during the stand-still periods. Practical tests have shown that the total loss of heat occurring between two running periods can thus be considerably reduced.

In many instances the available space does not permit to arrange the second slide or damper 5 at such a distance from damper 4 that the air inlet mechanism shown in Figs. 1 and 2 can be arranged between both slides or dampers. Also the operating mechanism for the air inlet device may be annoying since it will frequently have to be arranged in the passages of the boiler house. In order to do away with this inconvenience and to facilitate the mounting of the installation we construct according to Figs. 3, 4 and 5 a multiple or compound damper mechanism having a plurality of guiding ledges, so that one guide or pair of guides pertains to one damper or slide respectively. This compound damper mechanism is guided for vertical movement in a damper guiding frame interposed in the flue between the boiler or furnace and stack and again constitutes a separate space or compartment adapted to communicate with the outer atmosphere by means of an air inlet mechanism, when being in its lowered or operative position, care being again taken that no leakage by-pass communication can exist between the stack side and the boiler side of flue 2 around the space or compartment between the two slides or dampers.

The arrangement of two groups of guiding ledges, one group for each slide member or damper, is therefore of importance, since it permits that the draft or vacuum of the stack can only act on the air within the compartment between the two slides or dampers and have no influence on the air pressure conditions which prevail within the boiler side of flue 2, that is between the compound damper structure and the boiler structure.

According then to Figs. 3, 4 and 5 we arrange in the guiding frame 20 two vertical grooves or channels 21 and 22 co-operating

with two transverse members 23 having guiding ledges 24, 25 respectively and being rigidly connected with two damper plates or slides 26 and 27 by countersunk bolts 28 (Fig. 4). The two plates 26, 27 and their connecting members 23 are thus constituting as a unitary self-contained structure a compound hollow smoke damper being at its upper end closed by flaps 29. In the lowered position of this compound damper (Fig. 3) the flaps are automatically opened by pushrods 30 loosely sliding in bearings 31, whereby atmospheric air is admitted to the hollow space between the two plates 26 and 27 and can slowly be sucked off to the stack through the leakage between the guiding ledges of the stack-adjacent damper plate and its guiding channels of frame 20, the operation being thus exactly the same as that of the embodiment Figs. 1 and 2 at which both slides or dampers may be independently operated. Upon the damper being lifted by means of lifting rod 32 and a suitable kind of hoisting mechanism the rods 30 will slide down and permit the flaps 29 to close.

The compound damper as such must of course be well calked against the outer air. To this end the frame 20 is at its upper end provided with two transverse pocket-shaped beams 33 supporting rollers 34 which by their gravity always contact with the plates 26 and 27, whereby the gap is bridged which must always exist between the masonry or the damper frame 20 and the damper. The members 23 must however also be calked against the outer air between the guiding ledges 24 and 25 in order to prevent an air entrance into flue 2 while the boiler and the stack are in their normal operation. We therefore provide in the members 23 channels 35 adapted to receive one roller 36 respectively carried in chambers 37 of the damper guiding frame 20 and which are by gravity always held in airtight contact with the members 23, lugs 38 being provided on the guiding frame 20 and extending into the channels 35 for the support of the rollers 36. In order that the objectionable direct or by-pass connection between the stack side and the boiler side of the flue may be avoided we provide a communication of the space between the damper plates 26, 27, the cross wall 39 of the members 23 and the cross walls of frame 20 with the space between the damper plates 26 and 27 and the cross wall 39 by arranging air passages 40 in the lower ends of the walls 39. Accordingly the stack draft can again not act past the ledges 24 which may for example be on the boiler side of flue 2 on the air within the boiler side of flue 2 and within the boiler flues.

By the arrangement of the space or com-

partment adapted to communicate by leakage with the stack and to communicate by a valve mechanism with the outer air the stack draft can only suck off air from this 5 space or compartment through the sufficiently large air inlet orifice and there always exists within this space or compartment a slight vacuum which is a little below atmospheric pressure. Accordingly and in the absence 0 of any direct or by-pass leakage connection between the stack side and the boiler side of the flue around the space or compartment no heat can be carried off by flowing air from the boiler flues into the stack; what 5 will be discharged may eventually be the small gas quantities resulting from the belated burning down of some suspended fine coke particles.

What we claim as our invention is:

- 0 1. A smoke damper apparatus for interrupting the smoke flue communication between a stack and a fire place comprising a smoke flue, a plurality of flue obstructing slides adapted to establish in the smoke flue 5 a separate compartment so that any by-pass communication between the stack and the fire place and at the exclusion of the said compartment is prevented, and means for admitting air into the said compartment.
- 0 2. A smoke damper apparatus for interrupting the smoke flue communication between a stack and a fire place comprising a smoke flue, a plurality of movable dampers adapted to establish, when in their one operative position in the smoke flue, a separate compartment having leakage communication with the stack side and with the fire place side of the smoke flue at the exclusion 0 of any direct leakage connection between both smoke flue sides past the said compartment, and automatic means for admitting air into the said compartment when the dampers are in their compartment establishing positions.
- 5 3. A compound damper comprising a pair of rigidly connected distanced damper plates movable into and out of operative position, guiding means therefor adapted to constitute part of a smoke flue and permitting leakage connection of the space intermediate the damper plates with the adjoining flue portions while preventing any direct connection of the said flue portions at the exclusion of such intermediate space 5 and means for admitting air into the space intermediate the damper plates.
- 0 4. A compound damper comprising a pair of rigidly connected distanced damper plates movable into and out of operative

position and adapted to separate from a 60 smoke flue a closed compartment when being in the one operative position, a guiding frame having lateral walls adapted to be in substantial alignment with adjoining walls of a smoke flue and permitting in their co-operation with the damper plates a leakage connection of the space intermediate the damper plates with the outside of the said plates and at the exclusion of any direct by-pass connection of the said outside past the 70 said intermediate space, covers closing the space between the two damper plates and means for automatically opening the said covers and for admitting air into the said intermediate space when the two damper 75 plates are in their operative position.

5. A compound damper comprising a pair of rigidly connected distanced damper plates movable between an operative and an inoperative position, a guiding frame adapted to constitute part of a smoke flue and so co-operating with the said damper plate that a leakage connection of flue ends adjoining the guiding frame with the space intermediate the said damper plates is permitted while any direct by-pass connection of the adjoining flue ends at the exclusion of such intermediate space is prevented, covers closing the space intermediate the said damper plates and automatic means 80 adapted to lift the cover plates and admit air into the said intermediate space, when the damper plates are in their operative position and to close the cover plates and cut out the air admission, when the damper 85 plates are being moved into their inoperative position.

6. A compound damper plate comprising a pair of rigidly connected distanced damper plates, a guiding frame therefor adapted to 100 provide leakage connection between the space intermediate the said plates and the space outside the said guide and damper plates, transverse walls for connecting the said damper plates and being arranged at 105 a distance from the adjacent walls of the guiding frame, roller means for preventing leakage between the damper plate structure and its guiding means and means for establishing a permanent communication between 110 the space intermediate the damper plates and the spaces intermediate the transverse walls and the guiding frame.

In testimony whereof we affix our signatures.
